UND MASCHINENFABRIK, OF DUSSELDORF-DEERENDORF, GERMANY, A CORPORA-
TION OF GERMANY.

FUSE FOR PROJECTILES.

1,105,394.

Specification of Letters Patent. Patented July 28, 1914.

Application filed August 27, 1913. Serial No. 786,923.

To all whom it may concern:

Be it known that I, KARL ASA, foreman, a subject of the King of Norway, residing at Raufoss, Norway, have invented certain new and useful Improvements in Fuses for Projectiles; and I do hereby declare the following to be a full, clear, and exact description of the invention, such as will enable others skilled in the art to which it appertains to make and use the same.

The present invention relates to a fuse for projectiles having a plurality of timing rings, and the object of the invention is to so couple a fixed timing ring to the body 15 that adjustable rings located on opposite sides of such fixed ring may be axially turned in unison without interfering with the fixed ring. This is accomplished by coupling the fixed ring with the body by 20 means of a plurality of separate elements, such as pins, disposed in parallelism with the axis of the fuse and loosely fitted in openings in the fixed ring, their inner ends taking in recesses in the fuse body. The adjustable rings are fixedly secured to a sleeve 25 rotatably mounted on the body, the sleeve having a slotted flange at its inner end through which are passed the pins connecting the fixed ring to the body. This flange 30 is provided with means for displacing some of the coupling pins to permit the sleeve and its rings to be completely rotated in either direction, but the distance apart of the pins is such that at least one pin connects the 35 fixed timing ring with the fuse body in all positions of the sleeve.

In the construction according to the invention shown in the accompanying drawing, Figure 1 is a sectional elevation of the 40 fuse on the line 1-1 of Fig. 3. Fig. 2 is an elevation with parts of the fuse and body removed. Fig. 3 is a cross section and Fig. 4 a diagrammatic view. Figs. 5 and 6 are 45 respectively a section through and a plan view of the sleeve.

Referring to the drawings, the body *a* of the fuse has a central projection or socket *b* in the outer end of which are mounted a time plunger *c* and its priming cap *d*, the 50 latter being designed to be thrown rearwardly as against the action of a restraining spring *e* by the initial impulse on firing, whereupon the priming cap is perforated by the firing pin *f*. The ignition is 55 transmitted in known manner through the

channels *g* to the time ignition device. At the same time a powder pellet *h*, which forms a transport and loading safety device for the plunger *i* of the percussion fuse, is ignited, thus freeing the plunger *i* so that 60 the priming cap *k*, which is located therein, can be impelled on impact against the pin *l* secured to the fuse body.

The socket *b* forms a bearing upon which are mounted a plurality of timing rings, the outermost, *m*, being rigidly connected with the socket in any preferred manner. The second ring, *n*, and the fourth, *o*, are fixedly secured to and designed to turn with a sleeve *p* which is loosely mounted on the 70 socket *b*, the ring *n* being keyed to the cylindrical portion of the sleeve and the ring *o* to an outwardly projecting flange at the inner end of the sleeve. The third timing ring, *q*, which is relatively stationary, surrounds the sleeve *p*, but has no connection therewith. This ring which is coupled to the fuse body by means of pins *r*, lies between the rings *n* and *o*. To permit rings *n* and *o* to move in unison without uncoupling ring *q*, the out-turned flange of the sleeve *p*, which intersects the plane of the pins *r*, has segmental slots *s* through which the pins extend. These pins at their inner ends fit in shallow recesses in body *a*, their outer ends taking in holes in ring *q*. The recesses in the body *a* are part of a circular groove *v* extending around the body, the portions of the groove between these recesses being of less width than the diameter of 85 the recesses, but of the same depth, thus preventing any relative rotation between the pins and the fuse body. To allow of uninterrupted turning of the rings *n* and *o*, and sleeve *p*, I provide the flange of the latter at the points between the segmental slots with opposite projections *u* having each two beveled surfaces *t* which fit in the groove *v*, and which in the turning of the sleeve will successively engage the inner 90 ends of pins *r* and raise them to allow complete turning of the adjustable rings, the pins being lifted from one slot and dropped into the other. To permit the pins to be shifted, the ring *n*, is cut away on its under surface at points in line with the projections *u* on the sleeve. It will be observed that by use of a plurality of pins the ring *q* is at all times coupled with the body, turning 100 of the sleeve and the raising of the pins 105 110

affecting only a minority of the latter, the major portion of the pins remaining in coupling position. The beveled surfaces t being on both sides of the projections u enable 5 the sleeve to be turned in either direction.

I claim as my invention:

1. A fuse comprising a body, a plurality of relatively movable timing rings, one timing ring being coupled to the body, movable 10 elements for effecting such coupling, and means for displacing said elements without affecting the position of said coupled ring.
2. A fuse comprising a body, a plurality of timing rings, one timing ring being coupled to the body, movable elements for effecting such coupling, and means carried by a movable ring for successively displacing said elements as said latter ring is rotated.
3. A fuse comprising a body, a plurality 20 of timing rings, one timing ring being coupled to the body, a series of movable pins for effecting such coupling, and means carried by a movable ring for successively displacing said pins as said latter ring is rotated.
4. A fuse comprising a body, a plurality 25 of fixed timing rings, a plurality of adjustable timing rings alternately arranged in respect to the fixed timing rings, a series of coupling elements for locking one of said 30 fixed timing rings to the body, and means carried by the adjustable timing rings for displacing said coupling elements as the adjustable rings are rotated.
5. A fuse comprising a body, a plurality 35 of fixed timing rings, a plurality of adjustable timing rings alternately arranged in respect to the fixed timing rings, a series of shiftable pins for locking one of said fixed timing rings to the body, and means carried 40 by the adjustable timing rings for displacing said coupling pins as the adjustable rings are rotated.
6. A fuse comprising a body, adjustable timing rings, a fixed timing ring interposed 45 between said adjustable rings, shiftable pins

for locking the fixed timing ring to the body, a sleeve carrying said adjustable timing rings, and means carried by said sleeve for successively displacing said pin as said adjustable rings are rotated.

7. A fuse comprising a body, adjustable timing rings, a fixed timing ring interposed between said adjustable timing rings, shiftable pins for locking the fixed timing ring to the body, a sleeve carrying said adjustable 55 timing rings, said sleeve having a flange at its inner end formed with slots through which said pins project, and means carried by said sleeve for successively displacing said pins as said adjustable rings are rotated. 60

8. A fuse comprising a body, adjustable timing rings, a fixed timing ring interposed between said adjustable timing rings, shiftable pins for locking the fixed timing ring to the body, a sleeve carrying said adjustable 65 timing rings, said sleeve having a flange at its inner end formed with slots through which said pins project, and also having beveled portions for engaging said pins for successively unlocking them from said body. 70

9. A fuse comprising a body having a circular groove and spaced-apart recesses opening into said groove, a fixed timing ring, pins carried by said fixed timing ring designed to fit into said recesses, inner and 75 outer adjustable timing rings between which said fixed timing ring is located, a sleeve connecting said adjustable timing rings having a slotted flange at its inner end, and oppositely inclined portions between said slots 80 for fitting in said grooves and successively engaging said pins.

In testimony whereof, I have signed this specification in the presence of two subscribing witnesses.
